IMPRVMT**

(76) Inventors: **John C. Boyd; Andrew Kitchin**

John C. Boyd and Andrew Witchin
Letters Patent.

The Schedule referred to in these Letters Patent and making part of the same containing a description in the words of the said John C. Boyd and Andrew Witchin themselves of their improvement on Heth Ballou's thrashing machine.

Our improvement on Heth Ballou's thrashing machine, which must be considered the basis of this invention consists in having a riddle of a semi circular form, instead of a flat one, whereby the grain after having passed under the breaking or thrashing cylinder is guided round down to the wire, riddle, or separator, instead of being obstructed in its progress or passage and causing it to have a tendency to go back to the point from whence it came. And likewise make improvement on wire, riddle, or separator, hung in the usual manner is constructed with a wooden frame inside of which, made of sheet iron or tin, is put the riddle. That part which is nearest to the thrashing machine, about $\frac{1}{3}$ of its length is without holes, for the purpose of acting as a guide or way to the straw, and grain to prevent its falling through on account of its perpendicular descent, before the chaff is separated from it. The holes can be round or square: round we deem the best, and their jagged or by downwardly.

Boyd.
